UNITED STATES PATENT OFFICE.

JOHANNES CHRISTIAN JOHANSEN, OF LONDON, ENGLAND.

MASSAGE APPARATUS.

1,177,415.

Specification of Letters Patent. Patented Mar. 28, 1916.

Application filed August 8, 1911. Serial No. 642,935.

To all whom it may concern:

Be it known that I, JOHANNES CHRISTIAN JOHANSEN, a subject of the King of Denmark, residing at 48 Welbeck street, Cavendish Square, London, England, have invented certain new and useful Improvements in Massage Apparatus, of which the following is a specification.

My invention relates to improvements in massage apparatus of that kind in which a rocking motion is imparted to the tool or implement which effects the massaging or tapping treatment. Such instruments have been provided with protecting cups, arms or devices, but such protectors have only been provided in connection with single armed tools having a single tapping action whereas the object of my invention is to provide a tapping tool with which instead of the ordinary single tapping or vibratory effect, an alternating double tapping effect is produced, that is to say the rocking member is rocked so that two tools or tapping surfaces are alternately brought into operation, preferably symmetrically on either side of the longitudinal axis of the instrument, guides or protecting surfaces being provided at either side or around the tool or tools or surfaces. I may also provide means for adjusting in an easy manner, the extent of the rocking motion.

In the accompanying drawings an instrument with my present improvements is illustrated, Figure 1 being a longitudinal section of the implement; Fig. 2 being a plan view thereof; Fig. 3 a longitudinal section taken at right angles to Fig. 1.

The instrument comprises a suitable casing or frame *a* in which is arranged the gearing for imparting motion to the tool or tapping device. This gearing may be of any suitable description and is here shown as hand driven and consisting of a handle *b* shaft *c* and multiplying pinions *d*, *d'*, *d''*, *d'''*. The latter is mounted upon a shaft *e* upon which is also provided an eccentric or cam *f* working in a corresponding passage or recess in the end of a sleeve *g* in which the rod or stem *g'* of a pivoted member *g''* is arranged in such manner that the two parts *g*, *g'* can have a slight telescopic motion when the sleeve *g* is rocked by the eccentric. These parts *g*, *g''* constitute the rocking member which is pivoted about an axle *g''* mounted in the casing *a*.

The top of the rocking member is formed or provided with a tapping tool or surface *h*, herein shown as a plate secured centrally to the rocking member and having its sides substantially level with the top of the casing *a* or of guides *i* secured thereto. The operative surfaces of the tool, which is preferably removable and adjustable, can be, as shown, flat or substantially flat plates, or the tool may consist of a forked lever, carrying balls or other operative surfaces which may be adjustable at its free ends, symmetrically arranged on either side of the center, and mounted in a suitable manner on the rocking member. A hole *g''* can also be provided in this member to receive the stem of a suitable frictional tool, such as a ball.

It will be observed that the tapping plate *h* consists of a strip of metal having a central transverse channel whereby it is secured to the rocking member. This is a very efficient form of tapping member since the arms or wings on either side can be somewhat springy and this contributes to the vibratory nature of the tool.

On either side of the tapping member *h* I arrange protective and support plates *i*, here shown as metal plates screwed to the sides of the casing and having outwardly extending flanges *i'* substantially level with the outer surface of the tapping tool. These guides in the first place protect the tapping tool from accidental injury while they also prevent the latter from being pressed with such force against the patient as to stop the action of the tool. Obviously the protecting device or devices could extend completely around the tool if desired, the main object being, as stated, to prevent the tool being pressed too forcibly against the part being operated upon. In those cases where the protecting devices are not integral parts of the casing or frame they must be adjustable and removable.

It will be readily understood that when the handle *b* is turned the shaft *e* will be rapidly rotated, causing, through the eccentric *f*, the member *g*, *g''* to rock about its pivot *g''* thereby causing the arms of the tool *h* to give alternate strokes against the part to which the tool is applied.

While the method illustrated in Figs. 1 and 3 of effecting the rocking motion of the tool is a suitable one it can be effected in other ways.

While I have described the instrument as being provided with means for operating the tool by hand, it will be evident that it can be driven electrically or mechanically.

5 What I claim and desire to secure by Letters Patent is:

1. A massage device comprising a casing, a pivoted rocking member therein, a double-headed tapping tool secured to the rocking member so as to be positively rocked with it, and protective flanges forming extensions of the casing on either side of the tool substantially as set forth.

2. A massage device comprising a casing, 15 a pivoted rocking member therein, a double headed tapping tool consisting of a centrally depressed plate secured to said member and operative flanges on either side of said central depression, and protective 20 flanges forming extensions of the casing on

either side of the flanged plate substantially as set forth.

3. A massage device comprising a casing, a pivoted rocking member therein, a double headed tool *h* secured centrally to said member, and flanged plates *i*' on either side of said tool, substantially as set forth.

4. A massage device comprising a casing, a pivoted rocking member therein, a double headed tapping tool consisting of a plate 30 having a central transverse channel whereby the plate is secured to said rocking member and flanged plates on either side of said double headed tool.

In testimony whereof I affix my signature 35 in presence of two witnesses.

JOHANNES CHRISTIAN JOHANSEN.
